UNITED STATES PATENT OFFICE.

TIMOTHY A. BRESNAHAN, OF LYNN, MASSACHUSETTS, ASSIGNOR TO BRESNAHAN BROS., OF SAME PLACE.

SOLE-SHAPING MACHINE.

SPECIFICATION forming part of Letters Patent No. 409,269, dated August 20, 1889.

Application filed December 10, 1887. Serial No. 257,500. (No model.)

To all whom it may concern:

Be it known that I, TIMOTHY A. BRESNAHAN, of Lynn, in the county of Essex and Commonwealth of Massachusetts, have invented certain new and useful Improvements in Boot and Shoe Sole Shaping Machines, of which the following, taken in connection with the accompanying drawings, is a specification.

This invention relates to machinery for shaping boot and shoe soles after they are attached to the shoe-upper. It is an improvement on the machine described in Letters Patent of the United States numbered 300,039, dated June 10, 1884, and has for its object to provide mechanism for applying compressive force to the sole intermittently. It relates, also, to minor improvements in matters of construction, all to be hereinafter fully described, and pointed out in the claims.

20 In the drawings, Figure 1 is a plan view of a machine embodying two duplicate sets of mechanism, and each set embodying my invention. Fig. 2 is a side elevation with some of the parts in section.

25 For a description of details of construction and mechanism and as an aid in understanding this invention, reference may be had to the Letters Patent No. 300,039.

The working parts of the machine are 30 mounted upon a frame-work A. The form for supporting the boot or shoe has a foot portion B, shaped like an ordinary last, always with due respect to the shape of the intended sole. It is mounted, as shown, on the rock- 35 shaft C, in order, first, that it may be turned upward to facilitate putting on and taking off the shoe, and, second, to allow movement necessary to permit the form B to adapt itself to the mold D when brought against the same 40 under pressure. The mold D is formed with due regard to the style of the intended sole, all in the usual manner. It is detachably connected to a block E, which block E has its lateral edges grooved or concaved to fit the 45 rod P P, by and between which it is supported, and along which it is reciprocated longitudinally for the purpose of carrying the mold up to and away from the sole. Said block bears its rear face against the rod H, by which it is 50 pressed forward. The contiguous faces of these parts are rounded and the block permits

slight oscillating movement, to the end that it may adapt itself to the inequalities of the sole.

The rod H is arranged, as shown, in block R, 55 and is provided with a suitable thread adapted to work in screw-wheel M, also mounted in the block R, in such manner that turning the wheel operates to move the rod longitudinally in the block. Said block R has its lateral 60 edges grooved or concaved to fit the rods P P, by and between which it is supported and along which it is reciprocated longitudinally for the purpose of forcing the mold forward against the sole. The said longitudinal move- 65 ment of the block R is effected by the toggle-arms a a, and these, in turn, are operated by a suitable crank-and-lever mechanism, as shown in the drawings, and more fully described in Letters Patent No. 300,039, above referred 70 to. The toggle-arms a a engage one with the sliding block R, and the other with a plunger e, arranged to permit sliding movement in the barrel b. Said barrel is mounted upon and fixed to the machine-frame, and has a chamber 75 for holding the spring f, which spring is coiled spirally around the plunger-rod, as shown, and bears one end against the rear face of the plunger and its opposite end against the barrel-head, as shown, and this, it will be under- 80 stood, gives a yielding quality to the pressure applied for driving the mold forward and compressing the sole into shape.

In operating the machine the workman first draws the shoe over the form D while the 85 form is turned up, as shown in Fig. 2. He then turns the form into line with the mold D, and, placing one foot on the lever d, he moves the same sufficiently to bring the toggle-arms, composed of parts 7 7, forward and slightly 90 past the "center line," as shown in Fig. 2, in which position they are held by the projections 6 6 in an obvious way. The next upward throw of the crank-shaft 8 will bring upward the toggle-arms a a, thereby contracting the 95 spring f and driving forward the form D against the shoe-sole for the purpose of molding and shaping the same.

The compressive force, it will be observed, is applied to the mold through the intermediate spring f, which gives a yielding quality to the pressure. The compressive force is de- 100

veloped by contracting the spring, and is greatest when the spring is most contracted; and this occurs when the toggle-arms *a a* are lifted to an approximately straight line, as shown in Fig. 1. This takes place when the crank mechanism is at its highest lifting-point, and the next movement of the crank depresses the toggle-arms *a a*, and thereby allows the spring *f* to expand and remove pressure from the sole. The pressure is reapplied by the next upward movement of the crank, as before described, and so on. The pressure is applied and withdrawn alternately during each complete revolution of the crank, and the shoe-sole is thus compressed intermittently, to the end that any hard bunches in the leather may be worked down to an even and uniform surface.

It is desirable that the sole should be subjected to the action of the shaping mechanism for a considerable time, (more or less,) depending upon the kind of work, and for the purposes of convenience, as well as economy in manufacture and use, several sets of mechanism—a half-dozen, more or less—may be united in one frame and run by one driving-shaft. The workman, having adjusted a shoe in one set of mechanism, may turn his attention to placing a shoe on the next adjoining set of mechanism, and so on he passes through the entire set and comes back to the first shoe,

which by this time has been quite molded and is ready to be removed.

I claim and desire by Letters Patent to secure—

1. In a machine for shaping boot and shoe soles, a form, as *B*, for supporting the shoe, a mold, as *D*, for shaping the sole, toggle-levers *a a*, means for operating them, a barrel *b* in rear of one of the levers, a spring inclosed in said barrel, and a plunger in connection with the lever *a*, fitting said barrel and adapted to be acted upon by the spring therein, substantially as described. 35

2. In a boot and shoe sole shaping mechanism of substantially the construction described, and in combination, the described form for supporting the shoe, a mold, as *D*, for shaping the sole, a movable block for supporting the mold and adapted to permit a rocking movement, as described, a rod, as *H*, adapted to bear upon and press forward the block, said block and rod having their contiguous faces rounded, and connecting and operating mechanism, substantially as described. 45

Signed at Lynn, Massachusetts, this 1st day of December, A. D. 1887.

TIMOTHY A. BRESNAHAN.
